United States Patent Office

Des. 185,407
Patented June 2, 1959

185,407

FOOT PROTECTOR OR SIMILAR ARTICLE

Hideo Yamaguchi, Kurume, Japan, assignor to Nikka
Rubber Co., Ltd., Kurume City, Japan

Application April 3, 1957, Serial No. 45,560

Term of patent 14 years

(Cl. D7—7)

Fig. 1 is a top plan view of a foot protector or similar article showing my new design;

Fig. 2 is a side elevational view thereof;

Fig. 3 is a bottom plan view thereof.

I claim:

The ornamental design for a foot protector or similar article, substantially as shown.

References Cited in the file of this patent

UNITED STATES PATENTS

D. 97,499	Morali	-----	Nov. 12, 1935
D. 131,408	Harms	-----	Feb. 17, 1942